SANITARY APPLICATOR

Filed June 13, 1944

UNITED STATES PATENT OFFICE

2,404,815

SANITARY APPLICATOR

Frank Satz and Mel Berns, Los Angeles, Calif.;
said Satz assignor of one-half of his right to
Samuel Sontag, Los Angeles, Calif.

Application June 13, 1944, Serial No. 540,170

9 Claims. (Cl. 206—56)

1

This invention relates generally to applicators and more particularly to devices for applying cosmetics and other substances.

An object of the invention is to provide a device for supporting and applying cosmetics and other articles, which is structurally characterized by a handle-forming case having sections adapted to define a cover for a cosmetic stick or other article, and being movably mounted to open or close the case, according as the article is projected from the case for use, or is retracted into the case, all by a simple manipulation performed by the same hand in which the device is held, thus leaving the other hand free to hold a mirror or other article for the use of same as the cosmetic stick is being applied.

Another object of the invention is to provide a sanitary applicator in which the cosmetic stick or other article will be fully protected against contamination, yet can be instantly moved to a projected position for convenient use, all in such manner as to dispense with extraneous parts such as a separate cap or closure requiring two-hand manipulation to open and close the case, with the attending possible annoyance of misplacing or losing such closure.

A further object of the invention is to provide a device of the above described character which can be inexpensively and durably constructed entirely of plastics; is simple in construction; positive in operation by one hand; effectively seals in the cosmetic stick or other article against contamination so that the device can be carried about on the person or in the hand bag in a sanitary condition; and which presents the compact, attractive streamlined appearance particularly desirable in feminine accessories of this nature.

With these and other objects in view, the invention resides in the combinations, arrangements and functional relationships of elements set forth in the following specification and particularly pointed out in the appended claims.

In the accompanying drawing:

Figure 1 is a view in side elevation, of the sanitary applicator embodying this invention;

Figure 2 is an enlarged longitudinal sectional view showing the case closed;

Figure 3 is a view similar to Figure 2 and showing the case open;

Figure 4 is a longitudinal sectional view taken on the line 4—4 of Figure 2;

Figures 5 and 6 are transverse sectional views taken, respectively, on the lines 5—5 and 6—6 of Figures 2 and 4 respectively.

Referring specifically to the drawing, the in-

2

vention in its illustrated embodiment comprises a case A which functions as a handle in the use of the invention, and is composed of an open-ended cylindrical tube 10 of suitable plastic or other material, having one end seating in a circular recess 11 in a cap 12, and permanently secured thereto by acetate or other suitable means. Close to its open end, the tube 10 is provided at diametrically opposed locations with rectangular openings 13 in which seat rectangular lugs 14 on bearing elements 15 of streamlined shape which are permanently secured on the tube 10 by acetate or other means.

The bearing elements 15 are provided with bearing recesses 16 opening internally of the tube 10, in which are freely received pivot lugs 17 formed on guide fins 18 of the two sections 19 of a streamlined cover B, to rockably mount the sections on the case A for movement to occupy the closed and open positions shown in Figures 2 and 3 respectively. In their closed positions the cover sections co-act to define a chamber 20 (Figure 2) forming a continuation of the open end of the case A and adapted to enclose a cosmetic stick C or other article, the stick being fitted at one end in a circular socket 22 of a support D formed by intersecting guide webs 24 and 25, and slidably mounted in a guide element in the form of an open-ended tube 26, one end 30 of which is permanently secured in an annular recess 27 formed in the cap 12 to dispose the guide tube concentrically of and in spaced relation to the tube 10.

The other end of the guide tube 26 projects beyond the corresponding end of the tube 10 and is provided at diametrically opposed locations with longitudinal slots 30 receiving the guide fins 18 to confine the cover sections 19 to their opening and closing movements, and prevent relative lateral displacement and misalignment of the cover sections about the pivot lugs 17.

At its upper end, the guide web 24 of the article support D is prolonged outwardly of the socket 22 so as to also project into the guide slots 30 of the guide tube 26, and these portions of the web are formed to provide a convex curved cam 35 and a wedging cam 36 adapted to co-act with cam surfaces 37 and 38 respectively, on the guide fins 18 of the cover sections 19 in a manner to be later described.

Projecting radially from the web 25 of the article support D, through registering longitudinal slots 40 and 41 in the tubes 10 and 26 respectively, are diametrically opposed arms 42, on the outer projecting ends of which are secured by ace-

tate or other means, streamlined knobs or buttons 43 which constitute finger pieces to move the support D and the article carried thereby, axially of the case A to occupy an advanced position for use of the article, or a retracted position within the case, in synchronism with opening and closing movements of the cover sections 19, in the operation of the invention which is as follows:

With the cover sections 19 closed as shown in Figures 2 and 4, the wedge cams 36 on the article support D jam against the complementarily shaped cam surfaces 38 of the cover sections 19 to maintain the latter tightly closed, with the cover sections clear of the cosmetic stick C so that the latter will be sealed in the portion of the case A formed by the chamber 20, and will be fully protected thereby against contamination. It will be noted that by the wedging co-action of the cams 36 and cam surfaces 38, the cover sections will be effectively locked against opening movement so that ordinary handling of the device will not displace the cover sections from their fully closed positions.

To expose the article C for use, it is only necessary to manipulate one knob 43 or the other by a finger of the hand in which the device is being held, so as to move the knob along the respective slot 40 from the position shown in Figure 4, which movement first causes the cams 35 to engage the cam surfaces 37 and instantly rock the cover sections 19 to their maximum open position shown in broken lines in Figure 3, so as to permit free and unobstructed axial movement of the cosmetic stick C to its advanced position beyond the cover sections, for use as desired.

As the advancing axial movement of the article support D from its retracted position is continued, the cover sections 19 are free to return to the minimum open position shown in full lines in Figure 3, to which position they are limited by engagement of the cams 35 with the outer end portions of the cover sections, Figure 3, so as to maintain the cover sections clear of the cosmetic stick. Upon reversely actuating the knob 43 to effect axial retracting movement of the article support D, the cams 36 on the latter will again engage the cam surfaces 38 of the cover sections and will positively move the latter to, and lock them in closed position during the final portion of such retracting movement, so that a full length cosmetic stick will have been previously disposed wholly within the cover sections in the chamber 20, and be clear of the cover sections.

It will be manifest from the foregoing description that the opening and closing movements of the cover sections 19 are positively controlled in synchronism with the axial advancing and retracting movements of the article support D, and that the cover sections will be positively confined against lateral displacement and misalignment about their "floating" pivot lugs 17 by the co-action of their fins 18 with the slots 30 of the guide tube 26. Thus, under the wedging action of the cams 36 and cam surfaces 38, the cover sections will close tightly to adequately protect the cosmetic stick or other article against contamination, and will be positively opened by the co-acting cams 35 and cam surfaces 37 to freely pass the cosmetic stick to its projected position for use, all while enabling an extremely simple fulcrum-forming means to be used to mount the cover sections for opening and closing movements.

We claim:

1. A device of the class described comprising: an elongated case having an open end; a guide

tube supported in said case in spaced relation to the sides thereof and projecting beyond said open end of the case; a plurality of cover sections; means mounting the cover sections on the case between said sides thereof and said guide tube, for movement laterally of the case to open and close said end of the case, in which latter position the sections co-act to form a chamber in which said projecting portion of the guide tube is received; an article support mounted in said guide tube for movement axially thereof to occupy retracted and advanced positions; said cover sections and support having means operable to open or close the cover sections according as said support is advanced or retracted; and actuating means projecting from said support through said guide tube and wall of the case for movement axially of the case to actuate the support.

2. A device of the class described comprising: an elongated case having an open end; a guide tube supported in and projecting from said end of the case in spaced relation to the sides thereof and having longitudinal slots therein; a plurality of cover sections receiving the guide tube therebetween, and mounted on the case between said sides thereof and said guide tube, for movement laterally of the case to occupy an open position and a closed position, in which latter said cover sections co-act to form an article receiving chamber beyond said open end of the case; an article support reciprocably mounted in said guide tube for movement axially thereof to occupy a retracted position and an advanced position, in which latter an article carried by the support will project beyond the cover sections for use; said support and cover sections having co-acting cam means operable through said guide slots to move the cover sections to open or closed position according as said support is advanced or retracted; and means connected to said support by which the latter can be actuated.

3. A device of the class described comprising: an elongated case having an open end; a guide tube supported in said case in spaced relation to the sides thereof and having longitudinal slots therein; a plurality of cover sections mounted on the case between said sides thereof and said guide tube, for movement laterally of the case to occupy an open position and a closed position, in which latter said cover sections co-act to form an article receiving chamber beyond said open end of the case; an article support reciprocably mounted in said guide tube for movement axially thereof to occupy a retracted position and an advanced position, in which latter an article carried by the support will project beyond the cover sections for use; said support and cover sections having co-acting cam means operable through said guide slots to move the cover sections to open or closed position according as said support is advanced or retracted; and means connected to the support by which the latter can be actuated; said cover sections having guide portions working in said slots of the guide tube for co-action therewith in maintaining the cover sections in aligned relationship.

4. A device of the class described comprising: an elongated case having an open end; a guide tube supported in said case in spaced relation to the sides thereof and having longitudinal slots therein; a plurality of cover sections having guide fins working in the said slots of the guide tube, with portions of the fins defining pivot lugs co-acting with the case to mount the cover sections between said sides of the case and said guide

tube, for movement laterally of the case, to open and close an end of the latter; an article support mounted in said guide tube for movement axially thereof to occupy advanced and retracted positions; co-acting cam means on the support and on said fins of the cover sections, operable to move the latter to open or closed positions according as said support is advanced or retracted; and means connected to said support by which the latter can be actuated.

5. A device of the class described comprising: an elongated case; a guide element supported in the case in spaced relation to the sides thereof; a plurality of cover sections rockably mounted on the case between said sides of the case and the guide element, for movement laterally of the case to open and close an end thereof; the cover sections and guide element having co-acting means to maintain said sections in alined relationship; an article support reciprocably mounted in the guide element to occupy retracted and advanced positions; means on said cover sections and support co-acting to open or close the cover sections according as the support is advanced or retracted; and means connected to the support by which the latter can be actuated.

6. A device of the class described comprising: a tubular case having bearing recesses; a guide tube rigidly supported in the case and having slots; cover sections having pivot lugs working in said bearing recesses to mount the cover sections on the case for rocking movement laterally thereof to open and close an end of the case; means on the cover sections received in said guide tube slots to maintain the cover sections in alined relationship; an article support mounted in the guide tube for advancing and retracting movements axially of the case; co-acting means on said support and cover sections operable through the guide tube slots to open or close said sections according as said support is advanced or retracted; and means connected to the support by which the latter can be actuated.

7. A device of the class described comprising: a tubular case having bearing recesses; a guide tube rigidly supported in the case and having slots; cover sections having pivot lugs working in said bearing recesses to loosely mount the cover

sections on the case for rocking movement laterally thereof to open and close an end of the case; means on the cover sections received in said guide tube slots to maintain the cover sections in alined relationship; an article support mounted in the guide tube for advancing and retracting movements axially of the case; co-acting means on said support and cover sections operable through the guide tube slots to open or close said sections according as said support is advanced or retracted; and means for actuating the support.

8. A device of the class described comprising: an elongated case having an open end; a guide tube supported in said case in spaced relation to the sides thereof and having longitudinal slots therein; a plurality of cover sections having guide fins working in said slots of the guide tube, with portions of the fins defining pivot lugs co-acting with the case to mount the cover sections between said sides of the case and said guide tube, for movement laterally of the case, to open and close an end of the latter; an article support mounted in said guide tube for movement axially thereof to occupy advanced and retracted positions; and means operable to move the cover sections to open or closed position according as said support is advanced or retracted.

9. A device of the class described comprising: an elongated case having an open end; a guide tube supported in said case in spaced relation to the sides thereof and having longitudinal slots therein; a plurality of cover sections having guide fins working in the slots of the guide tube and being provided with means mounting the cover sections on the case for movement laterally thereof to open and close said end of the case; an article support mounted in the guide tube for movement axially thereof to occupy advanced and retracted positions; co-acting cam means on the support and on said fins of the cover sections, operable to move the latter to open or closed position according as said support is advanced or retracted; and means by which the support can be actuated from exteriorly of the case.
